PORTABLE MOTOR-ASPIRATED PSYCHROMETER

Rutger B. Colt and Alexander Uchuck, Baltimore, Md.,
assignors to Bendix Aviation Corporation, Baltimore,
Md., a corporation of Delaware

Application August 22, 1956, Serial No. 42,702

Term of patent 14 years

(Cl. D52—7)

FIG. 1.

FIG. 2.

FIG. 3.

Figure 1 is a frontal perspective view of a portable motor-aspirated psychrometer illustrating our new design;

Figure 2 is another perspective view but looking from the opposite side of the instrument of Figure 1; and

Figure 3 is a bottom plan of the instrument.

The dominant features of the design reside in the portions shown in full lines.

We claim:

The ornamental design for a portable motor-aspirated psychrometer, as shown and described.
